UNITED STATES PATENT OFFICE.

CHRISTIAN F. HESS, OF CHICAGO, ILLINOIS, ASSIGNOR TO ALEXANDER NELSON, OF CHICAGO, ILLINOIS.

VALVE-GRINDER.

1,155,489.

Specification of Letters Patent.

Patented Oct. 5, 1915.

Application filed June 22, 1914. Serial No. 348,484.

To all whom it may concern:

Be it known that I, CHRISTIAN F. HESS, a citizen of the United States of America, and resident of Chicago, Cook county, Illinois, have invented a certain new and useful Improvement in Valve-Grinders, of which the following is a specification.

My invention relates to devices for grinding the valves for internal combustion engines. This, it will be understood, is usually accomplished by rotating the valve back and forth on its seat until the latter and the surface of the valve have been made smooth. In this way, and after an engine 10 valve has become worn or impaired by use, it can be repaired and restored to such a condition that it will not leak. Devices have been proposed and used for grinding a valve in this way. So far as I am aware, however, these devices have not been altogether satisfactory.

The object of my invention is, therefore, to provide a novel and inexpensive valve grinder which can be easily and conveniently operated to rotate the valve on its seat and which can be employed in situations or places heretofore more or less inaccessible to other devices, as will hereinafter more fully appear.

30 To these and other useful ends my invention consists in matters hereinafter set forth and claimed.

In the accompanying drawings—Figure 1 is a perspective of a valve grinder embodying the principles of my invention, showing the same in position to engage the valve, which latter is also shown in perspective directly below. Fig. 2 is a side elevation of the valve grinder, showing certain portions 35 thereof in vertical section.

As thus illustrated, my invention comprises a two-prong tool A having its prongs a adapted to enter the openings in the top of the valve B, these openings b being disposed in suitable position for this purpose. The said tool has a shank or stem a¹ provided at its upper end with a swivel hand grip or handle C, which latter is adapted to fit the palm of the hand, and is similar to the handle of an ordinary carpenter's brace and bit. This handle is provided on its under surface with a plate c which has a swivel connection c¹ with the upper end of the stem or shank a¹, and is held in place by screws c², whereby 50 the said handle may remain stationary in

one hand while the tool is being rotated back and forth by the other hand. The means for producing this back and forth rotation, in order to turn the valve B back and forth on its seat, comprises a laterally projecting arm a² which is rigid with the said tool A, and which has an upturned outer end portion a³, this upturned end portion preferably terminating short of the plane of the under side of the handle C, as shown more clearly in Fig. 2. The handle D is provided with a downturned end portion d having a ball d¹ which engages a socket a⁴ in the upper end of the portion a³, whereby the said handle can be swung up or down or sidewise relative to the tool. The edge portions a⁵ of the said socket are bent or swaged inward a little to hold the ball d¹ in place.

The mode of operation is as follows:—The handle C is grasped by the user in one hand, and the prongs a are then inserted in the openings of the valve. The other handle D is then grasped by the other hand, and by means of this handle the tool A is then rotated longitudinally of the stem a¹—that is to say, about an axis extending centrally of the handle C and the said valve. This, it will be seen, is accomplished by moving the handle D back and forth in a manner to swing the arm a² from one side to the other. During this time, the handle D may be held at the most convenient angle, and is not necessarily held in a plane parallel with the plane of the arm a², for the reason that the ball and socket joint permits perfect freedom of manipulation of the handle D in any suitable or desired manner. In this way, and by reason of the provision of the handle D and the ball and socket connection thereof, the valve grinder thus embodying the principles of my invention can be used in places and situations which have heretofore been more or less inaccessible to the other devices which were employed for this purpose.

With my improved construction the operation of twisting the valve back and forth is comparatively easy, and is accomplished with greater convenience and less physical discomfort than was heretofore possible with certain other devices.

The stem a¹ serves as a stop to limit the swing of the handle in either direction in a plane at right angles to the axis of the tool. Also, it will be seen, the handle is movable

to a limited extent out of said plane, and has some rocking motion about an axis extending lengthwise thereof. The edge of the socket can be formed to keep the handle from dropping down to a greater extent than is shown in dotted lines in Fig. 2. At the same time sufficient flexibility is afforded between the handle and arm to insure convenient operation of the tool under cramped 10 or awkward conditions.

It will be seen that the construction is very simple and inexpensive in character. A short section of round rod is bent into shape to provide the portions a^1 , a^2 , and a^3 , 15 and the ends of this U-shaped member are then suitably formed to receive the handle and grip. The tool A is connected with the corner of elbow of said U-shaped member in any suitable manner. The said handle D 20 has its proximal end attached to the distal end of the rod or arm. With this construction and arrangement of the parts the device is, moreover, easily operated in various places and under conditions which preclude 25 the use of certain other devices for this purpose.

What I claim as my invention is:—

1. A valve grinder comprising a tool for engaging the valve, a stem for said tool, a 30 hand grip swiveled on the end of said stem, an arm extending laterally from between the tool and said hand grip, said arm having its distal end bent toward the plane of said grip, said tool being rigid with the elbow 35 formed by said stem and arm, and a handle for operating said tool, movably connected at one end thereof to the distal end of said arm, having its outer end free, thereby adapted to swing around and assume different 40 angles relative to said arm.

2. A valve grinder comprising a tool for engaging the valve, a stem for said tool, a hand grip swiveled on the end of said stem, an arm extending laterally from between the 45 tool and said hand grip, and a handle for operating said tool, movably connected at one end thereof to said arm, having its outer end free, thereby adapted to swing around and assume different angles relative 50 to said arm, the connection between said handle and arm permitting said handle to swing about an axis parallel with the said stem, and also about another axis extending at right angles to said stem, the one axis extending at an angle to the other.

3. A valve grinder comprising a tool for engaging the valve, a stem for said tool, a hand grip swiveled on the end of said stem, an arm extending laterally from between the 60 tool and said hand grip, and a handle for operating said tool, movably connected at one end thereof to said arm, having its outer end free, thereby adapted to swing around and assume different angles relative 65 to said arm, said connection between the

arm and handle being a ball and socket joint permitting swinging motion of said handle in all directions.

4. A valve grinder comprising a tool for engaging the valve, a stem for said tool extending directly thereto, a hand grip swiveled on the end of said stem, an arm extending laterally from between the tool and said hand grip, integral with said stem, and a handle for operating said tool, movably 70 connected at one end thereof to said arm, having its outer end free, thereby adapted to swing around and assume different angles relative to said arm, said handle being mounted to swing in either direction until it encounters said stem, and to have a limited freedom of motion out of the general plane of such swinging movement, as well as some rocking motion about an axis extending 75 lengthwise thereof.

5. A valve grinder comprising a tool for engaging the valve, a stem for said tool, a hand grip swiveled on the end of said stem, an arm extending laterally from between the tool and said hand grip, and a handle for operating said tool, movably connected at 80 one end thereof to said arm, having its outer end free, thereby adapted to swing around and assume different angles relative to said arm, the connected end of said handle being 85 provided with a bent portion having a ball, and said arm having a bent portion provided with a socket for said ball.

6. A valve grinder comprising a tool for engaging the valve, a stem for said tool extending directly thereto, a hand grip swiveled on the end of said stem, an arm extending laterally from between the tool and said hand grip, integral with said stem, and a handle for operating said tool, movably 90 connected at one end thereof to the distal end of said arm, having its outer end free, thereby adapted to swing around and assume different angles relative to said arm, said 95 stem serving as a stop for said handle.

7. A valve grinder comprising a rod bent into the desired shape, a tool on the rod, a grip swiveled on one end of the rod, and a handle of suitable length having its proximal end swingingly connected to the other 110 end of said rod, said handle being operable to oscillate said tool about an axis coincident with the swivel of said grip.

8. A valve grinder comprising a rod bent into the desired shape, a tool on the rod, a grip swiveled on one end of the rod, and a handle of suitable length having its proximal end swingingly connected to the other end of said rod, said handle being operable 120 to oscillate said tool about an axis coincident with the swivel of said grip, and said rod being U-shaped with the lower portion thereof extending laterally of said axis.

9. A valve grinder comprising a rod bent into the desired shape, a tool on the rod, a 130

- grip swiveled on one end of the rod, and a handle of suitable length having its proximal end swingingly connected to the other end of said rod, said handle being operable to oscillate said tool about an axis coincident with the swivel of said grip, said handle connection including an elbow shaped portion having a ball and socket engagement with the rod.
- 10 10. A valve grinder comprising a rod bent into the desired shape, a tool on the rod, a grip swiveled on one end of the rod, and a handle of suitable length having its proximal end swingingly connected to the other
- end of said rod, said handle being operable to oscillate said tool about an axis coincident with the swivel of said grip, and said rod being U-shaped with the lower portion thereof extending laterally of said axis, the sides of said rod being of unequal height, and the shorter side being connected at its upper end with said handle.
- Signed by me at Chicago, Cook county, Illinois, this 8th day of June 1914.
- CHRISTIAN F. HESS.
